DESIGN FOR A MEAT MOLD

Edward Little, Saginaw, Mich.

Application November 1, 1935, Serial No. 59,324

Term of patent 3½ years

To all whom it may concern:

Be it known that I, Edward Little, a citizen of the United States, residing at Saginaw, county of Saginaw, State of Michigan, have invented a new, original, and ornamental Design for a Meat Mold, of which the following is a specification, reference being had to the accompanying drawing, forming part thereof.

Fig. 1 is a side view of a meat mold embodying my design.

Fig. 2 is a part sectional rear view taken on the line 2—2 of Fig. 1.

Fig. 3 is a perspective view, looking down from the top.

I claim:

The ornamental design for a meat mold, as shown.

EDWARD LITTLE.
